FIG. 1.

UNITED STATES PATENT OFFICE

2,482,968

SHOE PRESS

Ernest Dunford, St. Louis, Mo., assignor to Landis Machine Company, St. Louis, Mo.

Application November 12, 1947, Serial No. 785,209

9 Claims. (Cl. 12—33)

1

The invention relates to shoe presses, such as are commonly used in cementing a shoe sole or half sole to the shoe upper and for other operations and of the kind generally described in Patent No. 2,268,874, issued January 6, 1942, to C. L. Huntoon, and in a copending application Serial No. 717,946, filed December 23, 1946, by the present inventor, now Patent No. 2,437,942, issued March 16, 1948.

The main object of the invention is to equalize the pressure throughout the area of the shoe parts to be cemented together.

In each of the devices described in the above patent and copending application, the last supporting yoke is free to pivot relative to the actuating rods and to the deformable cushion. When movement of the last is opposed by the cushion, the legs of the yoke connected to the rods tend to align with the rods and the toe of the last presses the shoe sole toe portion into the cushion without exerting adequate pressure on the shoe sole rear portion. In attempting to secure adequate pressure on the shoe sole rear portion, the operator may strip the teeth from the gears of the operating mechanism.

Another object is to overcome these difficulties by providing a locking adjustment for the yoke to the rods so the last may be fixed at any desired angle to the cushion.

The above and other detail objects are attained by the structure illustrated in the accompanying drawings, in which:

Figure 1 is a side elevation of a shoe press constructed according to the invention and provided with a last supporting yoke adjustably locked to the actuating rods.

Figure 2 is a top view of the yoke and associated rods, and

Figure 3 is a transverse section taken approximately on the line 3—3 of Figure 1.

The shoe press comprises a frame 1 mounting a support 2 having a rigid tray-like main member 3 and a vertically adjustable segment 4. The support mounts a deformable cushion 8 upon which the bottom of the shoe S may rest. Vertical adjustment of segment 4 distorts cushion 8 and adapts the support for shoes having shanks at different angles to the soles, that is, for shoes with different heights of heels. Segment 4 has a depending pin 9 at each of its ends slidably received in bearings 10 in the rearwardly extending lugs 11 on member 3. Brackets 12 depend from the underside of member 3 and rotatably support a shaft 13 mounting a pair of cams 14 engaging pins 9. Segment 4 is raised and low-

ered relative to main member 3 by rotating shaft 13 and cams 14 by a handle 15. Each cam 14 has a series of indentations 16 in its periphery to receive the end of the corresponding pin 9 to hold segment 4 in adjusted position.

A shaft 17 operated by a handle 18 is journaled in frame 1 and has a worm 19 in mesh with the teeth of a crank wheel 20 journaled in the frame. Rods 21 and 21a at the sides of the frame are pivoted at one end to wheel crank pin 22 and at the other end to a yoke 23 which may be rotated about its longitudinal axis to different positions, as indicated in dot-dash lines in Figure 1, on pins 26 journaled in the rods and held against lengthwise movement by locking screws 27 in the yoke. Yoke 23 has a bayonet joint engagement with the end of an arm 24 on a last 25 which may be inserted within the shoe S. A locking bolt 28 through rod 21 and through a slotted lug 29 on yoke 23 secures the yoke against movement relative to the rods and provides for adjustment of the last at any desired angle to cushion 8.

Rotation of handle 18 causes crank pin 22 to draw rods 21 and 21a downwardly, thereby applying pressure through last 25 to the interior of the bottom of shoe S and thrusts the shoe sole against cushion 8. Yoke 23 and last 25 preferably are positioned on rods 21, 21a so that substantially uniform pressure is exerted on all parts of the shoe sole. Rods 21, 21a may be pivoted about crank pin 22 to position last 25 forwardly or rearwardly on cushion 8 and to change the direction of thrust on the last as described in the above patent.

The details of construction may be varied without departing from the spirit of the invention, and the exclusive use of those modifications coming within the scope of the claims is contemplated.

What is claimed is:

1. In a shoe press, cooperable pressure members, and means for moving one of said members with respect to the other member and comprising driving mechanism and an element pivoted to said mechanism and to said movable member, there being means to adjustably lock said movable member to said element at desired angles to said other member.

2. In a shoe press, a last-like pressure member including a yoke and arranged to oppose the inner part of a shoe, a cooperating pressure member arranged to oppose a corresponding outer part of the shoe, driving mechanism, an elongated element connected at its ends to said driving mecha-

nism and to said yoke, said last-like member being pivotally mounted on said element, and means for locking said last-like member against pivotal movement on said element.

3. In a shoe press, a stationary pressure member, a movable pressure member opposing said stationary member, and means for moving said movable member relative to said stationary member and comprising a driving mechanism and an elongated element pivoted at one end to said mechanism and at its other end to said movable member, there being means to adjustably lock said movable member to said element at desired angles to said stationary member.

4. In a shoe press, cooperable pressure members, and means for moving one of said members with respect to the other member and comprising a driving mechanism and an element pivoted to said mechanism and to said movable member and arranged to apply pressure through the latter from different directions when said element is pivoted to different positions on said mechanism, there being means to lock said movable member in a selected angular position relative to said element.

5. In a shoe press, a last-like pressure member including a yoke and arranged to oppose an inner part of a shoe, a cooperating pressure member arranged to oppose the corresponding outer part of the shoe, a driving mechanism, and linkage connecting said driving mechanism and said yoke, said yoke being mounted adjustably on said linkage, and means for fixing said yoke to said linkage with said last-like member at desired angles to said cooperating member.

6. Structure as described in claim 5 in which the yoke is pivoted on the linkage and the fixing means comprises a manually rotatable friction clamp spaced from the yoke and linkage pivot.

7. In a shoe press, a last-like pressure member including a yoke and arranged to oppose an inner part of a shoe, a cooperating pressure member ar-

ranged to oppose a corresponding outer part of the shoe, a driving mechanism, and linkage connecting said driving mechanism to the ends of said yoke, said yoke being mounted on said linkage for rotation about its axis tending longitudinally of the yoke, and means fixing the yoke to the linkage with said last-like member at a selected angle to said cooperating member.

5 8. In a shoe press, a last-like pressure member including a yoke element and arranged to oppose an inner part of a shoe, a cooperating pressure member arranged to oppose a corresponding outer part of the shoe, a driving mechanism, and a rod element connecting said driving mechanism and said yoke element, said yoke element being mounted for pivotal movement on said rod element and having a flange extending along said rod element, one of said elements having an arcuate slot about the pivotal connection between said elements, and means extending through said slot and engaging the other element for locking said elements together at desired angles.

15 9. In a shoe press, a frame forming a support for a shoe, a shaft extending through said frame beneath said support, means for rotating said shaft, cranks on the opposite ends of said shaft, links secured to said cranks and extending upwardly therefrom at the sides of said support, a yoke pivotally connected to the upright ends of 20 said links and adapted to mount a last in opposed relation to said support, and means for securing said yoke in selected pivotal position on said links.

35 ERNEST DUNFORD.
